DESIGN FOR A CASING FOR LIQUID DISPENSING APPARATUS

Herman O. Grimmeisen, West Springfield, Walter C. Leitch, Longmeadow, and Warren H. De Lancey, Springfield, Mass., assignors to Gilbert & Barker Manufacturing Company, West Springfield, Mass., a corporation of Massachusetts

Application July 15, 1938, Serial No. 78,518

Term of patent 14 years

To all whom it may concern:

Be it known that we, Herman O. Grimmeisen, Walter C. Leitch, and Warren H. De Lancey, citizens of the United States, residing at West Springfield, Longmeadow, and Springfield, respectively, in the county of Hampden and State of Massachusetts, have invented a new, original, and ornamental Design for a Casing for Liquid Dispensing Apparatus, of which the following is a specification, reference being had to the accompanying drawing, forming a part thereof.

Referring to the drawing:

Fig. 1 is a front elevational view of a liquid dispensing apparatus embodying our new design;

Fig. 2 is a side elevational view thereof; and

Fig. 3 is a top plan view thereof.

We claim:

The ornamental design for a casing for liquid dispensing apparatus, as shown.

HERMAN O. GRIMMEISEN.

WALTER C. LEITCH.

WARREN H. DE LANCEY.
